SYRINGE

Lawrence Rayman, Toledo, Ohio

Application June 26, 1947, Serial No. 757,253

1 Claim. (Cl. 128—218)

1

This invention relates to fluid injecting devices and more especially to devices of the syringe type for the injection of medicament or composition in hypodermic or intravenous injections.

The invention embraces the provision of means in combination with a fluid injection syringe whereby the amount of fluid to be drawn into or extruded from the syringe may be accurately determined.

An object of the invention is the provision of means engageable with spaced abutments or depressions formed on a syringe plunger for interrupting or retarding movement of the plunger, the spaces between the abutments or depressions representing pre-determined units of volume of contents in the syringe for injection purposes.

Another object of the invention is the provision of resilient means associated with a barrel of a syringe and cooperable with a serrated plunger for pre-determining by "feel" of the plunger movement the dosage of medicament or fluid ejected from the syringe.

Another object of the invention resides in the provision of a resilient means in combination with an injection syringe whereby a pre-determined unit or units of fluid may be extruded from the syringe without necessitating visual examination of the syringe.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is an elevational view of the syringe of the hypodermic type embodying a form of my invention;

Figure 2 is an enlarged longitudinal fragmentary sectional view taken substantially on the line 2—2 of Figure 1;

Figure 3 is a transverse sectional view taken substantially on the line 3—3 of Figure 1; and

Figure 4 is a detail view of a modified form of plunger forming an element of the invention.

While I have illustrated the arrangement of my invention as embodied in a syringe of the hypodermic type, it is to be understood that the measuring arrangement may be utilized with any form of fluid or material extruding mechanism.

Referring to the drawings in detail, the syringe

construction is inclusive of a cylindrically shaped member or barrel 10 fabricated of glass or other suitable material which has a hollow interior forming a tubular or cylindrical chamber 11. The barrel 10 is adapted to snugly yet slidably receive a plunger 12 also formed of glass or other suitable material. The plunger 12, while of a diameter permitting slidable movement of the plunger in the barrel 10, provides only a slight clearance space between the plunger and the interior wall of the barrel which is insufficient to permit fluid to flow between the walls of the barrel and plunger. The barrel 10 terminates at one end in a nipple 14 which is formed with a slightly tapered exterior surface arranged to frictionally receive the hollow shank portion 15 of a hypodermic needle 16. The needle 16 is formed with a very minute longitudinal channel 17 to permit the passage of fluid therethrough. The nipple 14 is provided with a channel 18 for establishing communication between the channel 17 of the needle and the interior of chamber 11. The exterior wall of the barrel 10 is provided with graduations or indications 20 in the form of lines inscribed transversely of the barrel 10 for indicating quantities of fluid that may be contained within the chamber 11. The graduations 20 provide a visual means for informing the user of the syringe as to the amount of fluid or material in the chamber 11 and serves visually to advise the user of the amount of fluid ejected from the chamber by movement of the plunger 12. The plunger 12 is formed at its outer extremity 22 with a thumb piece or button portion 22 which is integrally joined to the body portion by means of a tenon 23 of slightly reduced diameter. My invention is inclusive of simple yet effective means for mechanically informing the user of the syringe of the withdrawing or ejection of a pre-determined unit or amount of fluid. In accomplishing this result, the plunger 12 is provided with spaced circular depressions or recesses 24 formed in stacked alignment in the cylindrical exterior surface of the plunger. Means is provided resiliently engageable with the recesses for mechanically determining the extent of movement of the plunger 12 during a fluid ejecting operation. The mouth portion of the barrel 10 which is adapted to receive the plunger 12 is formed with spaced ridges or beads 26 and 27 forming together a circular recess or depression 28. A resilient clip or member 29, arranged for cooperation with the plunger 12 for fluid measuring purposes, is formed with an

annular portion 30 extending throughout a major portion circumferentially of the barrel 10 and is disposed in the recess 28 formed by the beads or ridges 26 and 27. The clip 29 is preferably formed of spring wire or other suitable material having resilient characteristics so that the inherent tension or stress in portion 30 serves to hold the clip in close frictional engagement in the recess 28 and prevent dislodgment of the clip. The clip 29 is of a cantilever type being formed with a radially extending portion 32 which takes over the bead 27 and is bent in the opposite direction as shown as 33 to form a V-shaped configuration as indicated in Figure 2, forming an apex or bight portion 34, the latter being arranged for slidable contact with the periphery of the plunger 12. The spring tension or inherent stress in the wire or metal of the clip serves to resiliently maintain the apex 34 at all times in frictional contact with the plunger 12.

In the use of the construction shown in Figures 1 through 3 inclusive, the user inserts the needle 16 into a receptacle containing fluid or medicament with the plunger telescoped to its innermost position within the barrel 10. The plunger 12 is then withdrawn relative to the cylinder while the needle 16 is inserted in the fluid, the fluid being thereby sucked up or aspirated into the chamber 11. The distances between the serrations 24 formed in the plunger of the barrel are made equivalent to pre-determined units of volume of fluid in the chamber 11. Thus, for example, the distance between adjacent recesses 24 may be the equivalent in volume to one half cubic centimeter of fluid in the chamber 11. It is to be understood that any other unit of measurement may be employed. The marks or serrations 20, disposed on the exterior surface of the barrel 10 may also be calibrated to the same volumetric units as those indicated by the distances between the serrations or recesses 24 on the plunger 12. As the plunger 12 is withdrawn in a right hand direction as viewed in Figure 1, to cause fluid without turning the plunger to be drawn into the chamber 11, the apex 34 of the clip 29 registers with each consecutive recess 24 so that the user is informed by the "feel" or added resistance to the plunger movement whenever the apex 34 engages in a recess. If more than one unit of fluid, indicated by the distance between successive recesses is desired, the user exerts further outward force upon the plunger 12 to disengage the apex 34 of the clip with a recess and, upon further movement of the plunger, the clip will again engage with the next successive recess. The resistance to further movement of the plunger again indicates to the user that a second unit of volume of fluid has been drawn into the chamber 11.

During ejection of the fluid from the syringe, the user of the syringe exerts pressure upon the thumb piece 22 of the plunger without turning the same to force the plunger 12 in a left hand direction as viewed in Figure 1 causing the plunger to extrude or eject fluid from the chamber 11. The user of the syringe will immediately notice an increase in resistance to the movement of the plunger until the apex 34 has been moved out of engagement with one recess. After this disengagement is effected the pressure required to move the plunger is decreased. As soon as the next suc-

ceeding recess 24 is moved into registration with the apex 34 of the clip, the movement of travel of the plunger will be temporarily interrupted because of the resilient force exerted by the clip in urging the apex 34 thereof into a recess or detent 24. This increase in resistance to movement of the plunger informs the user of the syringe that a pre-determined unit of fluid has been ejected from the syringe. By this means the syringe is well adapted for use not only by physicians but also by patients administering injections to themselves, as the desired dosage may be had independently of visual inspection of the graduations on the barrel. Thus a patient having defective eye sight is enabled to use the syringe and effect an injection of a pre-determined unit or units of medicament through the aid of mechanical measuring means for determining the quantity of fluid ejected from the syringe.

If desired the recesses or depressions may extend only partially around the barrel 12. As shown in Figure 4, the recesses 24 extend only partially around the plunger. Thus if it is desired to utilize the syringe without employing the recesses as measuring means, the plunger may be rotated to bring the clip 29 out of the locus of the recesses.

In both forms of the invention, the clip 29 not only serves as a means for mechanically measuring the amount of fluid drawn into or extruded from a syringe, but also functions as a friction means to prevent inadvertent removal of the plunger from the barrel 10 when the syringe is inverted.

It is apparent that, within the scope of the invention, modifications and different arrangements may be made other than as herein disclosed, and the present disclosure is illustrative merely of the invention comprehending all variations thereof.

What I claim is:

A hypodermic syringe comprising a barrel portion and a plunger, said plunger having a plurality of graduations formed thereon extending circumferentially thereabout, said graduations being in the form of depressions formed on the plunger, said depressions being coextensive in length and in stacked alignment, said barrel portion having a resilient cantilever type clip with converging clip elements forming a bight portion mounted externally thereon, the bight portion of said clip engaging the periphery of the plunger which extends outside of said barrel portion, and adapted to cooperate with said depressions in the plunger when the plunger is moved inwardly or outwardly in a straight line movement for resiliently restraining at the depressed portions the longitudinal displacement of the plunger, thereby facilitating measurement of units of fluid drawn into or ejected from said barrel.
